DECANTER

Robert S. Suttle, Los Angeles, Calif., assignor to Arrowhead and Puritas Waters Inc., Los Angeles, Calif., a corporation of California

Application December 16, 1954, Serial No. 33,582

Term of patent 14 years

(Cl. D58—6)

I claim:

The ornamental design for a decanter, as shown.
